By Frank L. Belknap. A.M.M.

UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

APPARATUS FOR CRACKING OIL

Application filed May 23, 1921, Serial No. 471,559. Renewed December 17, 1929.

This invention relates to improvements in process and apparatus for cracking oil and refers more particularly to that type of apparatus in which the oil is first passed through a continuous coil seated in a furnace, thence delivered to a vapor chamber where vaporization takes place, the vapors removed and certain of them returned as reflux condensate to the still for further cracking. In accordance with the present invention, the reflux condensate, while it is returned to the vapor chamber, is returned in such a way that it is kept out of contact with the main body of the carbon containing residue in the vapor chamber and is returned relatively clean to the heating coil for further treatment. The process may be operated, if desired, as a continuous process in which fresh charging stock is continuously fed to the heating coil and the carbon containing residue continuously drawn off from the expansion chamber.

The details of the invention will more clearly appear from the following description, together with the accompanying drawing, in which the single figure represents a view partly in side elevation and partly in vertical section of my improved apparatus.

Referring to the drawing:

1 designates a furnace in which is mounted the cracking coil 2, which may take the form of a series of 2 to 4 inch tubes connected to form a single continuous coil. The upper, or discharge end of the tubes is connected to an expansion or vapor chamber 3, which vapor chamber is provided with a residue draw off, pipe 4, controlled by throttle valve 5. The fresh oil is fed to the lower end of the coil through feed line 6, by means of feed pump 7, the feed line 6 having a suitable throttle valve 8.

Vapors pass out of the chamber 3 by means of the upwardly inclined vapor pipe 9, connected at its lower end to the top of the chamber 3, and at its upper end to the bottom of dephlegmator 10, which dephlegmator is provided with a plurality of baffles 11 and 12. The upper end of the dephlegmator is connected by vapor pipe 13, to the condenser coil 14, seated in condenser box

15. The lower end of the coil is connected by pipe 16 to the top of a receiver, 17. This receiver 17 is provided with pressure gauge 18, liquid level gauge 19, gas outlet pipe 20 controlled by throttle valve 21, and distillate 55 draw-off pipe 22 controlled by throttle valve 23. Throttle valves 24 and 25 may be inserted in the pipes 9 and 13, respectively, if desired. The arrangement is such that a vapor pressure may be maintained on all or 60 part of the system.

As a novel feature of the invention, the reflux condensate is continuously returned to the cracking coil for further treatment, but in such a way as to prevent it from being 65 mixed with the main body of the carbon containing residue. To this end the shell 3 is provided with the baffle member or partition member 26, which extends vertically upwardly and entirely across the inside of the 70 shell 3, but terminating short of the top of the shell 3, as shown in the drawings. The arrangement is such that the liquid level of oil in the shell 3 may be kept below the top of the partition member 26. The reflux condensate is prevented from falling back into 75 the shell 3 so as to mingle with the main body of the oil by providing the pipe line with a trap, 27. From the lower end of the trap, a pipe, 28, carries the reflux condensate 80 on into the shell 3 below the top of the partition 26 and on that side of the partition remote from the main body of the oil. This forms in effect a reflux containing compartment, 29, the lower end of which is connected by pipe 30, having throttle valve 31, with the main feed line, 6. It will thus be seen that the reflux condensate is returned directly to the heating coil, but passed through the shell 3. The process may be so 85 operated that no oil will over-flow the partition 26, by suitably regulating the liquid level of the oil in the chamber 3. In carrying out the process, the gas oil, fuel oil or crude petroleum treated may be fed continuously through the system and delivered in 90 substantial liquid phase at a temperature of 650 F. to 850 F. to the vapor chamber where vaporization takes place. A pressure of 95 from 50 lbs. to 350 lbs. may be maintained in 100

the entire system. The reflux condensate may be continuously returned via the pipes 28 and 30 to the heating coil for further treatment. If desired, a differential pressure may be maintained on the system by 5 suitably regulating the valves shown.

It will be noted, however, that the reflux condensate is never permitted to mix with the main body of the carbon containing residue. 10

I claim as my invention:

1. In an apparatus for cracking oil, the combination with a heating coil, of a furnace in which said coil is seated, an enlarged vapor chamber communicating with one end of the coil, a vertical partition disposed within said chamber near one side thereof and extending a considerable distance upwardly therein to thereby divide 15 the same and form a relatively small compartment at one side of the chamber, a vapor discharging line leading from said chamber, a dephlegmator communicating with said line, means for discharging reflux condensate directly into said relatively small 20 compartment at one side of the vapor chamber, a discharge line from the bottom of the compartment for admitting the reflux to the heating coil, and means for withdrawing 25 residual oil from the vapor chamber to maintain its level substantially below the upper portion of the partition.

2. In an apparatus for cracking oil, the combination with a heating coil, of a furnace in which said coil is seated, an enlarged vapor chamber communicating with one end of the coil, a vertical partition disposed within said vapor chamber near one side thereof and extending a considerable 30 distance upwardly within said chamber to form a relatively small compartment at one side of the chamber, a vapor discharge line leading from the chamber, a dephlegmator communicating with said line, 35 a vertically disposed discharge pipe leading from said line into said relatively small compartment for introducing a reflux condensate thereto, and a discharge pipe connected with the bottom of the compartment 40 for admitting reflux condensate to the heating coil, means for withdrawing residual oil from the vapor chamber to maintain its level below the upper portion of the partition, whereby the reflux condensate is 45 maintained separate from the residuum but is heated thereby prior to its introduction 50 to the heating coil.

GUSTAV EGLOFF.
